CLAIM

The ornamental design for a TV stand, as shown and described.

DESCRIPTION

FIG. 1 is a right-side perspective view of a TV stand showing our new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is an enlarged view of the area indicated by line 8 in FIG. 1.

The short-short-long broken lines are for notating enlarged views and form no part of the claimed design.

The evenly spaced broken lines indicate portions of the TV stand that form no part of the claimed design.
